REMOTE CONTROLLED TOY SHIP

Floyd R. Less, North Tonawanda, N. Y.

Application August 14, 1950, Serial No. 179,343

18 Claims. (Cl. 46—93)

1

This invention relates to amusement device and more particularly to a remotely controlled nautical toy.

The principal object of the invention is to move miniature ships by means which are entirely out of view of the observer and by which the ships can be caused to move in any desired direction as nearly as possible in the same manner as if they were propelled by their own power.

Another important object is to provide such means which permit the movements of the ship to be controlled from a place remote from the ship.

A further important object is to provide such means by which the ship is not compelled to follow any predetermined course but which permit the movements of the ship to be subject to change and control entirely at the will of the operator.

Other objects and advantages of the invention will be apparent from the following description and accompanying drawings in which:

Fig. 1 is a fragmentary perspective view of a miniature marine setting embodying the present invention.

Fig. 2 is a horizontal sectional view through the ship shown in Fig. 1 and showing the remotely controlled electrical responsive devices arranged within the ship for actuating the propeller and rudder of the ship.

Fig. 3 is a vertical generally central longitudinal view thereof.

Fig. 4 is a top plan view, on an enlarged scale, of the rails and movable carriage arranged thereon shown in Fig. 1.

Fig. 5 is a side elevational view thereof.

Fig. 6 is an enlarged fragmentary vertical sectional view of the means for connecting the electrical responsive devices carried by the ship with a remote source of controlled supply, this view being taken on line 6—6 of Fig. 2.

Fig. 6A is a perspective view of the connectable elements shown in Fig. 6 and showing these elements in a separated condition.

Fig. 7 is a horizontal sectional view thereof taken on line 7—7 of Fig. 6.

Fig. 8 is an enlarged fragmentary vertical sectional view of the means for connecting the lead wires extending from the ship to the movable carriage shown in Figs. 4 and 5, this view being taken generally on line 8—8 of Fig. 4.

Fig. 8A is a perspective view of the connectable elements shown in Fig. 8 and showing these elements in a separated condition.

Fig. 9 is an enlarged fragmentary vertical lon-

2

itudinal sectional view of a wheel assembly for the carriage shown in Figs. 4 and 5, this view being taken on line 9—9 of Fig. 4.

Fig. 10 is a fragmentary vertical transverse sectional view thereof taken on line 10—10 of Fig. 9.

Fig. 11 is an enlarged vertical central sectional view of the remotely located control unit shown in Fig. 1.

Fig. 12 is an elevational view of the left end thereof as shown in Fig. 11.

Fig. 13 is a top plan view thereof.

Fig. 14 is a wiring diagram of the electrical apparatus.

15 An amusement device illustrating one embodiment of the invention is shown in Fig. 1. The miniature marine setting illustrated in Fig. 1 is shown as including a box-like structure 20 formed with a depression which is filled with water preferably distilled water or any other suitable liquid to provide a lake 21. The contour of the lake can be as desired as well as the terrain surrounding the lake, that shown being solely intended as illustrative and not limitative of the practice of the invention.

20 A miniature ship or boat 22 which may be of any suitable type is shown as floating on the body of water or lake 21 and has a submerged propeller 23 and rudder 24 (Fig. 3). Electrical

30 responsive devices 25 and 26 are arranged within the ship for actuating the propeller 23 and rudder 24 respectively (Figs. 2 and 3). The operation of these electrical responsive devices 25 and 26 is under control of a manually operated con-

35 trol unit indicated generally at 28 which may be located remote from the lake 21 such as on the shore as shown in Fig. 1. The means for electrically connecting the control unit 28 with the electrical responsive devices 25 and 26 within

40 the ship 22 include stationary conductors indicated generally at 29 submerged in the lake and connected with the control unit 28, conductive pick-up devices indicated generally at 30 and movably arranged on the conductors 29, and

45 conductive means indicated generally at 31 connecting the pick-up devices with the electrical responsive devices 25 and 26 in the ship 22.

Referring to Figs. 2 and 3, the ship 22 is shown as having a hull 32 housing the electrical responsive devices 25 and 26. The propeller 23 is shown as fast to the rear end of a shaft 33 which is suitably journalled on the hull. The front end of this shaft 33 is suitably connected to and adapted to be driven by the electrical responsive device 25 which may be of any suit-

able type and is preferably a reversible electric motor of the direct current type.

The rudder 24 is shown as extending laterally from the lower end of a vertically arranged shaft 34 suitably journaled on the hull 32. While any suitable mechanical means may be employed for turning the rudder 24, that shown includes a pulley 35 fast to the upper end of the shaft 34 and a belt or cord 36 which passes around the rear side of the pulley 35 and has its opposite ends connected to the ends of a rock lever 38. This rock lever 38 extends horizontally transversely of the hull of the ship and is pivotally supported centrally of its ends on a bracket 39 which is connected to the hull. The axis of the generally vertical pivotal mounting of the rock lever 38 is indicated at 40.

Referring to Figs. 2 and 3, two electrical responsive devices 26, which are preferably solenoids, are arranged in push-pull relation with respect to the rock lever 38. Each of the solenoids 26 is shown as comprising a coil 41 surrounding an elongated cylindrical tube 42 and arranged at the front end thereof, and a magnetically permeable cylindrical armature 43 slidably arranged within the tube 42. A rod or link 44 is shown as connecting the armature 43 of each solenoid with the corresponding end of the rock lever 38 and as extending axially of such armature.

The solenoids 26 are shown as arranged with their axes extending rearwardly and slightly upwardly and inwardly with respect to the hull 32 of the ship so as to be directed towards the ends of the rock lever 38. These solenoids are supported in this position on the hull 32 by front brackets 45 and a rear bracket 46, such brackets embracing exposed portions of the solenoid tubes 42 and being suitably connected to the hull.

It will be seen that by energizing one solenoid 26 and correspondingly deenergizing the other solenoid 26, the rock lever 38 can be swung about its pivot 40 and thereby turn the rudder in the desired direction and through the desired angle.

The reversible electric motor 25 and solenoids 26 are preferably operated on direct current having a voltage of from 12 to 15 volts. While this power may be derived from any suitable source it is preferably derived from the conventional household supply of alternating current at 110 volts. This alternating current is converted to direct current at the desired voltage. For this purpose, referring to the wiring diagram in Fig. 14, the A. C. lines are shown as connected to the primary coil of a transformer indicated at 48 and the secondary coil thereof is arranged in series with a rectifier 49 of any suitable type. Lines 50 and 51 connect this series secondary circuit with a double pole double throw switch 52 and thereby provide the desired D. C. voltage for operating the motor 25 and solenoids 26.

Still referring to Fig. 14, the switch 52 is adapted to engage either the contacts of branch lines 53 and 54 or the contacts of branch lines 55 and 56. The branch lines 53 and 55 are shown as connected to one side 58 of a main line and the branch lines 54 and 56 are connected to the other side 59 of this main line. The reversible electric motor 25 is shown as connected in series with a variable resistor or rheostat 60 and both these elements are arranged across the lines 58 and 59. Similarly the coils 41 of the two solenoids 26 are shown as individually connected in series with variable resistors or rheostats 61 and

62 respectively and each set of elements so provided is connected across the lines 58 and 59.

It will thus be seen that with the switch 52 engaging the contacts for the branch lines 53 and 54 the line 58 can be rendered positive and the line 59 negative so that the reversible electric motor 25 can be driven in one direction at a speed under control of the setting of the rheostat 60. This closed position of the switch can determine the forward motion of the ship 22. On the other hand, if the switch 52 engages the contacts for the branch lines 55 and 56 which contacts are in reversed relation to those for the branch lines 53 and 54, the line 59 will be positive and the line 58 negative. This will operate to drive the motor in a reverse direction and determine backward movement of the ship 22.

An incandescent lamp 63 is shown as arranged in the line 58 between the rheostat 62 and the branch line 53 and when illuminated indicates to the operator that the operating circuit is live. A fuse 64 is preferably included in the operating circuit and is shown as arranged in the line 59 between the adjacent coil 41 and the branch line 54.

Referring to Figs. 11-13, the control unit 23 is shown as having a hollow base 65 and a housing 66 supported on this base. Within the housing 66 the rheostats 61 and 62 are shown as arranged in horizontally spaced relation with their movable elements fast to a common shaft 68. This shaft 68 is arranged horizontally and has its opposite ends journaled on brackets 69, 69. A handwheel 70 is arranged between the rheostats 61 and 62 and is fast to the shaft 68. The housing 66 has a transverse opening 67 from which the outer marginal portion of the handwheel 70 projects.

Referring to Fig. 14, it will be noted that the rheostats 61 and 62 are arranged operatively opposite to each other. Thus if the handwheel 70 is turned in one direction the effective resistance of one of the rheostats 61 and 62 will be increased while the effective resistance of the other will be decreased correspondingly. The relation of the effective resistances of the rheostats reverses when the handwheel 70 is turned in the opposite direction. In this manner the coils 41 of the solenoids 26 are reversely energized and thereby the position of the rudder is controlled so as to steer the ship 22 as desired.

The rheostat 60 is also arranged within the housing 66 of the control unit 23 and is shown as supported by a bracket 71 in a position in which the spindle 72 for its rotatable element extends vertically upwardly through the top of the housing 66. A knob 73 is arranged on the upper end of the spindle 72 and facilitates adjustment of the rheostat 60.

Adjustment of the rheostat 60 controls the R. P. M. of the electric motor 25 and hence the speed of the ship 22.

For convenience, the switch 52 is shown as arranged on one end wall of the housing 66 on the outer side of which the fuse 64 is also mounted. The lamp 63 is preferably arranged in the hollow base 65 with its bulb portion visible through an opening 57 in the top of the base.

While Fig. 14 is a simplified wiring diagram of the electrical circuit, the actual means for electrically connecting the control unit with the electrical responsive devices 25 and 26 within the ship 22 include the stationary conductors 29 resting on the floor of the lake 21, the conductive pick-up devices 30 and the conductive means 31.

The stationary conductors 29 are shown as including four parallel rails 74, 75, 76, and 77 arranged in transversely spaced relation on blocks or ties 78 of insulating material. These rails 74, 75, 76 and 77 are electrically connected to the control unit 28 by a cable 79 which includes four wires each one of which is connected to a different rail as shown in Fig. 1. Three of these wires serve as the leads from the rheostats 60, 61 and 62 and the fourth wire serves as the common ground or the line 59 shown in Fig. 14.

The pick up devices indicated generally at 30 are shown as comprising wheel assemblies 80, 81, 82 and 83 riding respectively on the rails 74, 75, 76 and 77 (Fig. 4). These wheel assemblies support a block or frame 84 of insulating material and provide jointly therewith a carriage movable back and forth along the rails. Each of these wheel assemblies 80, 81, 82 and 83 is similar in construction and the construction of the wheel assembly 84, which is representative of the construction of all, is shown in detail in Figs. 9 and 10. As there shown, the wheel assembly 84 comprises an inverted channel shaped member having transversely spaced vertical side walls 85, 85 connected along their top edges by a horizontal web 86. A pair of wheels 88, 88 are arranged between the side walls 85, 85 and spaced longitudinally along the rail. Each wheel 88 is fast to an axle 89, the ends of which are journaled on the side walls 85, 85. The channel shaped member is arranged in an opening 90 provided in the carriage frame 84. To connect this member to the carriage frame and yet permit free movement of the wheel assembly relative to the frame, a horizontal rod 91 extends transversely through enlarged openings 92 provided in the side walls 85 and is firmly fastened at its ends to the frame 84. This rod 91 carries an upstanding rod 93 which projects upwardly through an enlarged opening 94 provided in the web 86. It will thus be seen that the channel member with its wheels mounted thereon is free to rock about the axis of the horizontal rod, move vertically with respect thereto, move slightly in a fore and aft direction relative thereto, as well as slightly axially thereof. Thus a self adjusting wheel assembly is provided which eliminates any tendency of the carriage to bind in its movement along the rails. This is important for a purpose hereinafter noted.

The wheel assemblies 80, 81, 82, and 83 are made of conductive material and are individually electrically connected through wires 95, 96, 97, 98 respectively to the corresponding one of a series of stationary contactors 99. Each of these stationary contactors is in the form of a hair pin having closed and open ends. The stationary contactors 99 are superposed one above the other and have their closed ends separated by a washer 100 of insulating material and held down against the upper surface of the block 84 in any suitable manner as by the screw 101. The wires 95, 96, 97 and 98 are shown as connected to the side walls 85 of the corresponding wheel assembly and to the closed ends of the stationary contactors 99 (Fig. 4).

The open ends of the stationary contactors 99 individually have wiping contact with the corresponding one of a series of rotatable superposed contact rings 102. These rings 102 are insulated one from the other by spacers 103. The side legs of each contactor 99 are biased toward each other so as to press firmly against the corresponding contact ring 102 the periphery of

which is preferably grooved to receive the side legs of the companion contactor.

The contact rings 102 and spacers 103 are part of a unitary structure which also includes an elbow shaped conduit 104 having a vertical neck portion extending upwardly from the ring assembly and a horizontal portion extending laterally from the upper end of the neck portion. The outer end of this horizontal portion of the conduit 104 is formed to provide a receptacle 105. This receptacle 105 has a series of four sockets 106 (Fig. 8A) spaced one from the other and each is connected by an individual wire 108 arranged within the conduit 104 to one of the contact rings 102.

The unitary structure so formed is mounted, on the carriage block 84 for rotation about a vertical axis. For this purpose, a depending spindle 109 is rotatably received in a hole in the block 84 and a hold down strap 110 extends over the uppermost contact ring 102 and has an opening through which the upstanding neck portion of the elbow conduit 104 extends. The ends of the strap 110 are fastened to the block 84 in any suitable manner as by the screws 111 arranged at opposite ends thereof.

It will thus be seen that the receptacle 105 mounted on the carriage frame 84 can swing about a vertical axis and at all times have its 30 sockets maintain constant electrical connection with the corresponding wheel assembly and in turn the corresponding rail, even while the carriage is moving along the rails.

Referring to Figs. 6 and 6A, the ship is provided with a receptacle 112 having four sockets 113. Three of these sockets are electrically connected with the electric motor 25 and the two solenoids 26 and the fourth of these sockets serves as a common electrical return for the operation 40 of these electrically responsive devices. For this purpose the receptacle 112 is arranged adjacent an opening 114 in the bottom of the hull 32 of the ship and is shown as carried on the lower end of a tubular member or shaft 115 which is 45 rotatably mounted on the hull. The support for the rotatable member 115 comprises an upstanding sleeve 116 arranged within the hull 32 and surrounding the opening 114. The upper end of this sleeve is narrow and provides a bearing 50 for the tubular member 115. A laterally extending arm 118 is arranged on the upper end of the sleeve 116 and provides a support for a series of four superposed stationary contactors 119 which are similar to the contactors 99. Spacers 55 120 of insulating material separate the closed ends of the contactors 119 from each other and these spacers and contactors are held down on the outer end of the support arm 118 by a screw 121.

60 The free inwardly biased ends of each of the stationary contactors 119 have a wiping contact with a contact ring 122 which is similar to the contact ring 102. Thus four contact rings 122 are provided and these are separated from each other by spacers 123 of insulating material. These contact rings 122 and spacers 123 are mounted on the upper end of the tubular member 115 and rotate therewith. A wire 124 arranged within the tubular member 115 connects 65 each of the contact rings 122 with the corresponding socket 113 of the receptacle 112. A nut 125 on the upper end of the tubular member 115 prevents the same from dropping out of the boat.

70 Lead wires 126 extend from the closed ends of the stationary contactors 119, three of these wires

being connected with the electric motor 25 and the two solenoids 26 and the fourth lead wire serving as a common ground therefor.

The conductive means indicated generally at 31 (Fig. 1), electrically connects the receptacles 105 and 112. Such means is in the form of a flexible cable 128 having a plug 129 at one end and a plug 130 at its opposite end. The cable 128 contains four wires which at opposite ends are connected to the prongs 131 and 132 of the plugs 129 and 130 respectively. The prongs 131 are adapted to be received by the sockets 106 and the prongs 132 are adapted to be received by the sockets 113.

Referring to Figs. 6A and 8A, it will be noted that the arrangement of the mating prongs and sockets is not symmetrical so that they can be connected only in the desired manner. This correct manner of connection is further insured by a lug 133 on the end face of the receptacle 112 fitting into a recess 134 in the end face of the plug 140 and a similar lug 135 on the receptacle 105 fitting into a recess 136 in the plug 129.

Reviewing all the electrical connections it will be seen that connection of the live sides of the rheostats 60, 61 and 62 with the respective and appropriate electrical responsive devices 25 and 26 arranged within the ship 22 can be easily maintained, as well as providing a common ground return for these devices.

It will be noted that the movements of the ship 22 as to direction and speed are entirely under the control of the operator who operates the remotely located control unit 28. The rail conductors 29 while only shown as straight can, if desired, include curved portions. As the ship 22 moves it will pull the flexible cable 128 and a sufficiently long cable will be provided to provide the desired lateral movement of the ship relative to the rails. The ship can also pull the carriage along the rails if a long distance of travel is desired, the wheel assemblies of the carriage being designed to provide a minimum of mechanical resistance to travel along the rails. Because of the swivel connection between the ends of the flexible cable 128 and the ship 22 and pick up devices 30, twisting of the cable is avoided as well as minimizing drag on the ship.

Other electrical responsive devices, such as lights and smoke generators, arranged on the ship can be actuated and controlled in a manner similar to that disclosed above for propulsion and steering purposes. This could be accomplished by providing other rails, pick-up devices and suitable electrical connections.

It will therefore be seen that the present invention provides a highly entertaining and educational amusement device which in practice is capable of taking many different forms. Accordingly, the scope of the invention is intended to be limited only as defined in the appended claims.

I claim:

1. In an amusement device including a body of water and a miniature ship floating thereon and having a propeller, the combination therewith of means for controlling the propulsion of said ship, comprising an electrical responsive device arranged to rotate said propeller upon actuation of said device, conductor means submerged in said body of water, conductive pick-up means movably arranged on said conductor means, conductive means connecting said pick-up means with said device, and means controlling the feed of current to said conductor means thereby to control the actuation of said device.

2. In an amusement device including a body of water and a miniature ship floating and movable thereon and having a rudder, the combination therewith of means for controlling the turning of said rudder to steer said ship, comprising an electrical responsive device arranged to turn said rudder upon actuation of said device, conductor means submerged in said body of water, conductive pick-up means movably arranged on said conductor means, conductive means connecting said pick-up means with said device, and means controlling the feed of current to said conductor means thereby to control the actuation of said device.

3. In an amusement device including a body of water and a miniature ship floating thereon and having a propeller and a rudder, the combination therewith of means for controlling the movements of said ship, comprising a first electrical responsive device arranged to turn said rudder upon actuation of said first device, a second electrical responsive device arranged to rotate said propeller upon actuation of said second device, conductor means submerged in said body of water, conductive pick-up means movably arranged on said conductor means, conductive means connecting said pick-up means with said electrical responsive devices, and means controlling the feed of current to said conductor means thereby to control the actuation of said electrical responsive devices.

4. In an amusement device including a body of water and a miniature ship floating thereon and having a propeller, the combination therewith of means for controlling the propulsion of said ship comprising an electric motor arranged on said ship to rotate said propeller upon energization of said motor, conductors submerged in said body of water, conductive pick-up devices movably arranged on said conductors, conductive means connecting said pick-up devices with said motor, and means controlling the flow of current through said conductors thereby to control the energization of said motor.

5. In an amusement device including a body of water and a miniature ship floating and movable thereon and having a rudder, the combination therewith of means for controlling the turning of said rudder to steer said ship, comprising a solenoid arranged on said ship to turn said rudder upon energization of said solenoid, conductors submerged in said body of water, conductive pick-up devices movably arranged on said conductors, conductive means connecting said pick-up devices with said solenoid, and means controlling the flow of current through said conductors thereby to control the energization of said solenoid.

6. In an amusement device including a body of water and a miniature ship floating and movable thereon and having a rudder, the combination therewith of means for controlling the turning of said rudder to steer said ship, comprising a lever connected to said rudder for turning the same, a pair of solenoids operatively connected to said lever in push-pull relation for moving said lever, conductors submerged in said body of water, conductive pick-up devices movably arranged on said conductors, conductive means connecting said pick-up devices with said solenoids, and means controlling the flow of current through said conductors thereby to control the reverse energization of said solenoids.

7. In an amusement device including a body of water and a miniature ship floating thereon and

having a propeller and a rudder, the combination therewith of means for controlling the movements of said ship, comprising an electric motor arranged on said ship to turn said propeller for propulsion of said ship, a solenoid arranged on said ship to turn said rudder for steering said ship, conductors submerged in said body of water, conductive pick-up devices movably arranged on said conductors, conductive means connecting said pick-up devices with said motor and solenoid, and means controlling the flow of current through said conductors thereby to control the energization of said motor and solenoid.

8. In an amusement device including a body of water and a miniature ship floating thereon and having a propeller and a rudder, the combination therewith of means for controlling the movements of said ship, comprising an electric motor arranged on said ship to turn said propeller for propulsion of said ship, a lever connected to said rudder for turning the same to steer the ship, a pair of solenoids operatively connected to said lever in push-pull relation for moving said lever, conductors submerged in said body of water, conductive pick-up devices movably arranged on said conductors, conductive means connecting said pick-up devices with said motor and solenoids, and means controlling the flow of current through said conductors thereby to control the energization of said motor and the reverse energization of said solenoids.

9. In an amusement device including a body of water and a miniature ship floating thereon and having a propeller and a rudder, the combination therewith of means for controlling the movements of said ship, comprising a first electrical responsive device arranged on said ship to turn said rudder upon actuation of said first device, a second electrical responsive device arranged on said ship to rotate said propeller upon actuation of said second device, conductor rails submerged in said body of water, a carriage movably arranged on said rails and having pick-up devices engaging said rails, flexible conductors connecting said pick-up devices with said electrical responsive devices, and means controlling the feed of current to said conductor rails thereby to control the actuation of said electrical responsive devices.

10. In an amusement device including a body of water and a miniature ship floating thereon and having a propeller and a rudder, the combination therewith of means for controlling the movements of said ship, comprising a first electrical responsive device arranged on said ship to turn said rudder upon actuation of said first device, a second electrical responsive device arranged on said ship to rotate said propeller upon actuation of said second device, a plurality of conductor rails submerged in said body of water, a carriage movably arranged on said rails and having pick-up devices engaging said rails, a flexible conductor for each of said electrical responsive devices and connecting the same with one of said pick-up devices, and means controlling the flow of current through each of said conductor rails thereby to control the actuation of said electrical responsive devices.

11. In an amusement device including a body of water and a miniature ship floating thereon and having a propeller and a rudder, the combination therewith of means for controlling the movements of said ship, comprising a first electrical responsive device arranged on said ship to turn said rudder upon actuation of said first de-

vice, a second electrical responsive device arranged on said ship to rotate said propeller upon actuation of said second device, a plurality of conductor rails submerged in said body of water, a carriage movably arranged on said rails and having pick-up devices engaging said rails, a current supply line connected at one end of each of said electrical responsive devices and extending from said ship through the bottom thereof, the other ends of said lines being connected to said pick-up devices, and means controlling the flow of current through each of said conductor rails thereby to control the actuation of said electrical responsive devices.

12. In an amusement device including a body of water and a miniature ship floating thereon and having a propeller and a rudder, the combination therewith of means for controlling the movements of said ship, comprising a first electrical responsive device arranged on said ship to turn said rudder upon actuation of said first device, a second electrical responsive device arranged on said ship to rotate said propeller upon actuation of said second device, means electrically connecting said electrical responsive devices to an outlet in the bottom of said ship, a plurality of conductor rails submerged in said body of water, a carriage movably arranged on said rails and having pick-up devices engaging said rails, a flexible cable removably connected at one end to said outlet and at its other end connected to said carriage, said cable including a current supply line for each of said electrical responsive devices and operatively connected to one of said pick-up devices, said ship being adapted to pull said carriage along said rails by said cable, and means controlling the flow of current through each of said conductor rails thereby to control the actuation of said electrical responsive devices.

13. In an amusement device including a body of water and a miniature ship floating thereon and having a propeller and a rudder, the combination therewith of means for controlling the movements of said ship, comprising a first electrical responsive device arranged on said ship to turn said rudder upon actuation of said first device, a second electrical responsive device arranged on said ship to rotate said propeller upon

actuation of said second device, a plurality of contacts arranged on said ship for rotation about a generally vertical axis and having access thereto through an opening in the bottom of said ship, means electrically connecting each of said electrical responsive devices to a different one of said contacts, a plurality of conductor rails submerged in said body of water, a carriage movably arranged on said rails and having pick-up devices engaging said rails, a plurality of contacts arranged on said carriage for rotation about a generally vertical axis, means electrically connecting each of said last mentioned contacts to a different one of said rails, a flexible cable removably connected at opposite ends to both sets of said contacts, said cable including a current supply line for each of said electrical responsive devices, said ship being adapted to pull said carriage along said rails by said cable, and means controlling the flow of current through each of said conductor rails thereby to control the actuation of said electrical responsive devices.

14. In an amusement device including a body of water and a miniature ship floating thereon and having a propeller and a rudder, the combination therewith of means for controlling the

movements of said ship, comprising a first electrical responsive device arranged on said ship to turn said rudder upon actuation of said first device, a second electrical responsive device arranged on said ship to rotate said propeller upon actuation of said second device, a plurality of conductor rails submerged in said body of water, a carriage arranged for movement along said rails and including a conductive wheel assembly engaging each of said rails, a flexible cable connected at one end to said ship and at its other end to said carriage and including a current supply line for each of said electrical responsive devices and operatively connected thereto and to one of said wheel assemblies, and means controlling the flow of current through each of said conductor rails thereby to control the actuation of said electrical responsive devices.

15. In an amusement device including a body of water and a miniature ship floating thereon and having a propeller and a rudder, the combination therewith of means for controlling the movements of said ship, comprising a first electrical responsive device arranged on said ship to turn said rudder upon actuation of said first device, a second electrical responsive device arranged on said ship to rotate said propeller upon actuation of said second device, a plurality of conductor rails submerged in said body of water and including a live rail for each of said electrical responsive devices and a ground rail, a carriage movably arranged on said rails and having pick-up devices contacting said rails, a flexible conductor for each of said pick-up devices and connected thereto, means connecting each of said flexible conductors having connection with said live rails with the corresponding one of said electrical responsive devices, means connecting said electrical responsive devices to that one of said flexible conductors which is connected to said ground rail, and means connected with said rails and arranged to control the independent feed of current to said live rails thereby to control the actuation of said electrical responsive devices.

16. In an amusement device including a body of water and a miniature ship floating thereon and having a propeller and a rudder, the combination therewith of means for controlling the movements of said ship, comprising a first electrical responsive device arranged on said ship to turn said rudder upon actuation of said first device, a second electrical responsive device arranged on said ship to rotate said propeller upon actuation of said second device, a plurality of conductor rails submerged in said body of water and including a live rail for each of said electrical responsive devices and a ground rail, a carriage movably arranged on said rails and having pick-up devices contacting said rails, a flexible conductor for each of said pick-up devices and connected thereto, means connecting each of said flexible conductors having connection with said live rails with the corresponding one of said electrical responsive devices, means connecting said electrical responsive devices to that one of said flexible conductors which is connected to said ground rail, and a control unit located remotely from said rails and operatively connected therewith and having a manually adjustable rheostat in circuit with each of said live rails thereby to control the actuation of said electrical responsive devices.

17. In an amusement device including a body

of water and a miniature ship floating thereon and having a propeller and a rudder, the combination therewith of means for controlling the movements of said ship, comprising an electric motor arranged on said ship to turn said propeller for propulsion of said ship, a lever connected to said rudder for turning the same to steer the ship, a pair of solenoids operatively connected to said lever in push-pull relation for moving said lever, a conductive track submerged in said body of water and including a live rail for said motor and for each of said solenoids and in addition a ground rail, a carriage arranged for movement along said rails and having pick-up devices contacting said rails, a flexible conductor for each of said pick-up devices and connected thereto, means connecting each of said flexible conductors having connection with said live rails with the corresponding one of said solenoids and motor, means connecting said motor and solenoids to that one of said flexible conductors which is connected to said ground rail, and a control unit located remotely from said rails and operatively connected therewith, said unit comprising a manually adjustable rheostat in circuit with each of said live rails thereby to control the actuation of said motor and solenoids and means connecting the rheostats for said solenoids in opposing operative relation whereby the effective resistance of one is increased while that of the other is decreased.

18. In an amusement device including a body of water and a miniature ship floating thereon and having a propeller and a rudder, the combination therewith of means for controlling the movements of said ship, comprising a reversible electric motor arranged on said ship to turn said propeller for propulsion of said ship, a solenoid arranged on said ship to turn said rudder for steering said ship, a plurality of conductor rails submerged in said body of water and including separate live rails for said motor and solenoid and a ground rail, a carriage movably arranged on said rails and having pick-up devices contacting said rails, a flexible conductor for each of said pick-up devices and connected thereto, means separately connecting said flexible conductors having connection with said live rails with said motor and solenoid, means connecting said motor and solenoid to that one of said flexible conductors which is connected to said ground rail, and a control unit located remotely from said rails and operatively connected therewith and comprising a manually adjustable rheostat in circuit with each of said live rails thereby to control the actuation of said motor and solenoid and a reversing switch arranged to reverse the polarity of said rails whereby the rotation of said motor is reversed.
